[57] CLAIM

The ornamental design for a combined soap holder and towel ring, substantially as shown and described.

DESCRIPTION

FIG. 1 is a perspective view of the combined soap holder and towel ring showing our new design;

FIG. 2 is a rear elevational view thereof;

FIG. 3 is a side elevational view taken from the left of FIG. 1;

FIG. 4 is a bottom plan view thereof;

FIG. 5 is a top plan view thereof.
